CLOCK

John L. Hancock, Villa Park, Ill., assignor to Master-crafters Clock Corporation, Chicago, Ill.

Filed Mar. 23, 1971, Ser. No. 127,428

Term of patent 7 years

Int. Cl. D10—01

U.S. Cl. D42—7

FIG. 1

FIG. 2

FIG. 3

FIG. 1 is a front perspective view of a clock embodying my new design;

FIG. 2 is a front elevational view with an interior element in a raised, exposed position; and

FIG. 3 is an end elevational view looking from the right of FIG. 2.

The end not shown is a mirror image of the end shown and the back is substantially plain and unornamented.

I claim:

The ornamental design for a clock, substantially as shown and described.
